UNITED STATES PATENT OFFICE.

WALTER D. BROSSMAN, OF BERTHOUD, COLORADO.

SWIMMING-MACHINE.

1,135,350.

Specification of Letters Patent.

Patented Apr. 13, 1915.

Application filed May 14, 1914. Serial No. 838,535.

To all whom it may concern:

Be it known that I, WALTER D. BROSSMAN, a citizen of the United States by birth, residing at Berthoud, in the county of Larimer and State of Colorado, have invented 5 certain new and useful Improvements in Swimming-Machines, of which the following is a specification.

This invention relates to swimming devices, and the primary object of the invention is the provision of a device which will retain a person upon the surface of the water, and which has associated therewith a propeller and suitable means manually 15 operable for controlling the propeller for propelling a person through the water.

With the foregoing and other objects in view, this invention consists in such novel features of construction, combination, and 20 arrangement of parts as will be hereinafter more fully described, illustrated in the accompanying drawings, and claimed.

In describing the invention in detail, reference will be had to the accompanying drawings, wherein like characters designate like or corresponding parts throughout the 25 several views, and in which:

Figure 1 is a side elevation of the improved swimming machine, Fig. 2 is an end 30 view of the swimming machine, and Fig. 3 is a cross sectional view on the line 3—3 of Fig. 1.

Referring more particularly to the drawings, 1 and 2 designate floats, which are constructed of any suitable material, preferably 35 of hermetically sealed metallic tubes, and they are connected one to the other by brackets 3 and 4, which brackets depend downwardly from the floats as is clearly 40 shown in Figs. 1 and 2 of the drawings. The bracket 3, which is positioned at the forward end of the floats 1 and 2, has a bracket 4 secured thereto, which bracket has journaled transversely therein a shaft 5. The shaft 5 45 has crank handles 6 and 7 mounted upon its opposite ends, which crank handles are positioned oppositely to each other, so as to provide a device which may be easily rotated by the hands of a person. The shaft 50 5 has a bevel gear 8 keyed thereupon, which bevel gear meshes with a bevel pinion 9. The bevel pinion 9 is formed upon one terminal end of the shaft 10, and through its 55 meshing engagement with the bevel gear 8, the rotary motion of the shaft 5 will be

transmitted to the shaft 10 for rotating the propeller 11, which is mounted upon the rear end of the shaft 10, and the rotation of the propeller 11 will force the device forwardly through the water.

The shaft 10 is rotatably journaled in a bearing which is formed in the lowermost portion of the bracket 4. Flexible straps 12 and 13 are attached to the floats 1 and 2, and suspended therebetween, which straps are 60 provided for supporting a person between the floats, so that the person may conveniently reach and operate the crank handles 7 for the propulsion of the device. The flexible straps 12 and 13 have one end thereof secured in any suitable manner to one of the floats 1 or 2, they being shown secured to the float 2 in Fig. 3 of the drawings, and they extend from one float to the other, entirely about the circumference of 65 the float 1, and having the free terminal end in overlapping engagement with the under surface of a part of the straps which are suspended between the two floats, and securely held thereagainst by suitable clamps 70 14 and 15, so that the straps may be adjusted for regulating the depth that the person riding upon the machine will be in the water.

In the operation of the improved swimming device as heretofore described, the person desiring to be propelled through the water will lie upon the straps 12 and 13, and operate the crank handles 6 and 7, which will in turn rotate the shaft 10 through the 75 medium of the bevel gear 8 and the bevel pinion 9, which will operate the propeller 11 for propelling the swimming device through the water. The crank handles 6 and 7 are positioned forwardly of the ends of the 80 floats, so that the floats will not interfere in the operation thereof.

In reducing the invention to practice, certain minor features of construction, combination, and arrangement of parts may necessitate alteration, to which the patentee is entitled, provided such alterations are comprehended within the scope of what is claimed.

What is claimed is:—

In a swimming device, a plurality of floats, brackets connecting said floats, a substantially U-shaped bracket connected centrally to the under surface of one of said first mentioned brackets, a plurality of op- 105 110

positely disposed crank handles journaled in said U-shaped bracket, a gear wheel mounted on said crank and disposed between said U-shaped bracket, a shaft extending longitudinally of said floats and rotatably supported by said first and second mentioned brackets, a propeller at one end of said shaft and a gear wheel on the opposite end, said gear wheel to mesh with the gear 10 carried by the crank for rotating said shaft,

and a flexible strap adjustably secured around said floats.

In testimony whereof I affix my signature in presence of witnesses.

WALTER D. BROSSMAN.
